UNITED STATES PATENT OFFICE.

WILLIAM F. KIESEL, JR., OF ALTOONA, PENNSYLVANIA.

RAILWAY-CAR FRAME.

No. 878,538.

Specification of Letters Patent.

Patented Feb. 11, 1908.

Application filed February 23, 1907. Serial No. 358,974.

To all whom it may concern:

Be it known that I, WILLIAM F. KIESEL, Jr., a citizen of the United States, residing at Altoona, in the county of Blair and State of Pennsylvania, have invented certain new and useful Improvements in Railway-Car Frames, of which the following is a specification.

This invention relates to improvements in the upper and lower deck framework for steel railway cars; my object being to provide certain modifications upon this portion of the framework as illustrated and described in my Letters Patent for improvements in railway car frames, No. 832,486, dated October 2, 1906, and No. 842,889, dated February 5, 1907, whereby I attain a more thorough bracing against end shock and side racking in the superstructure of the car frame, and materially lighten the weight of the component parts of the framework, without sacrificing strength or stiffness.

I attain my objects by constructing the several parts of the framework in the manner illustrated in the accompanying drawings, in which—

Figure 1 represents a side elevation of one end of a car embodying my improvements, portions of the outer sheathing being broken away to disclose the framework; Fig. 2, a side elevation on a larger scale of my improved framework, between the middle of the first panel and the end of the car; Fig. 3, an end elevation of the same, the right half of the figure being shown sectioned on the line *b*—*b* in Fig. 2; Fig. 4, a detail showing an end view of the end deck-plate 21, looking to the left in Fig. 2; Fig. 5, a transverse section of one-half of the upper framework 40 of the car on the line *a*—*a* in Fig. 1; Fig. 6, a transverse section on a larger scale of the deck-plate 5, on the line *a*—*a* in Fig. 1; Fig. 7, a side elevation of this portion of the framework over one of the main frame posts; Fig. 45 8, a detail showing an end view of one-half of one of the upper deck carlines on an enlarged scale; and Fig. 9, a horizontal section of the side deck casting 13, on the line *c*—*c* in Fig. 5.

Like numerals designate like parts throughout the several views.

The framework for the body of the car comprises, as described in my said Letters Patent, the box girder center sill 1, at each side of which angle bar side sills 2 are supported upon cross-bearers 3. From the side

sills, the main frame posts 4 rise at suitable intervals, dividing the car body into panels, said main frame posts being curved over at the top to form lower deck carlines, and being riveted at their upper ends to the deck side-plates 5, which extend longitudinally at each side of the car. These main frame posts are of U-shaped cross section, and will be found more fully described in my Letters Patent for improvement in carlines, No. 809,920, granted January 9, 1906. In my said prior patents, these upper carline extensions from the main frame posts are shown riveted to a longitudinal angle bar, which extends from one end of the car to the other at each side. In order to stiffen this angle bar, and also lighten the weight of the upper deck framework, I now combine the deck-plate with this angle bar, forming them in one integral piece; the stiffening flange 9, as shown on the deck-plate herein, taking the place of the said longitudinal angle bar. At the top, the deck-plate is flanged outwardly at 11, to receive the upper deck roof sheets, said flange being bent downwardly at 12 to form an eaves finish for the upper deck. The deck-plate, as so formed, comprises a comparatively light plate of steel stiffened by flanges at top and bottom edges and extending from one end of the car to the other; the web of the plate between the flanges 9 and 11 constituting the outer and inner sheathing for the car between decks. This web is cut through at proper intervals, as at 10, to receive the deck lights.

The lower flanges of the carline extensions on the main posts are riveted to the stiffening flanges 9 of the deck-plates, and are also turned up at the ends and riveted to the web of the deck-plates, as shown more clearly in Figs. 5 and 6; the flanges 9 being broad enough to receive two rows of rivets. Between the main frame posts lighter intermediate posts 6 rise from the sill plates 7, which are riveted in between the main posts back of the belt rail 8, as described in said Letters Patent; the upper ends of these intermediate posts being also bent inward to form lower deck carlines, and being riveted to the stiffening flanges 9.

The lower deck roof sheets 19, in this construction, are light steel plates, flanged along their upper edges, and riveted directly to the web of the deck-plates by means of the same rivets by which the deck side lights are secured in place. These roof sheets are then

bent down and riveted to the top of the post carlines, being carried over at the outer edges and riveted to the longitudinal stiffening braces 17, which pass along and are riveted to the posts on a line just above where they begin to curve inward to form the carline extensions. These longitudinal stiffening braces are also of U-shaped section, the lower flange being pressed outward and then downward at 18 to form an eaves molding. This form of longitudinal brace provides a light but stiff connection between the posts along the top of the car sides, and, by combining with it the eaves molding, I am enabled to materially lighten the construction, since the lower flange of the stiffening brace is riveted in between the lower edge of the roof sheets and the upper edge of the top-side-plate 20; the lower edge 20 of the roof sheets resting directly upon the ledges formed by the eaves molding and forming therewith a water tight joint.

Over the ends of each of the main frame posts, where their carline extensions are attached to the deck-plates 5, I provide side braces consisting of flanged castings 13, the lower flanges of which rest upon the lower deck roof sheets and are riveted through said sheets to the webs of the posts. The side flanges of these deck side-braces are riveted to the webs of the deck-plates, and the upper flanges support the eaves flanges 11, being riveted thereto by means of the same rivets by which the upper deck sheets are secured in place. Passing across between the upper ends of opposite side-braces are the upper deck carlines 14, which I now form of U-shaped cross section with the side flanges and webs bent downward at each end so as to 40 be riveted to the deck side-braces, with the deck-plates between. I thus simplify the construction of these upper deck carlines and yet retain the same degree of strength and stiffness in the upper frame work of the car. 45 Intermediate carlines 14 also pass across between deck-plates above the intermediate posts 6, the deck side-braces at these points being omitted. The upper deck carlines are connected together and braced longitudinally by the braces 15, which are also of U-shaped section, and upon the flanges of which the upper deck roof sheets 16 rest, said sheets being riveted directly to the flanges of the carlines and passing over at 55 their outer edges, at each side upon the eaves flanges 11, with which they form a water-tight and weatherproof joint.

The deck-plates 5, I prefer to make continuous throughout the length of the car; 60 but, by reason of the difficulty of obtaining such plates of sufficient length, they may be spliced, say at every third main post, the plate sections being joined together by butt joints, the deck-castings 13 and the lower and 65 upper deck carline flanges acting as splice

plates to hold the plate sections rigidly together, and there being two vertical rows of rivets on each plate section where the vertical flanges of the deck side-braces are riveted thereto, as shown more clearly in Fig. 7. At 70 each end of the car the deck-plates are united by butt joints, (see Fig. 2), to the end deck-plates 21; said end deck-plates being formed for a portion of their length to correspond with the main deck-plates; the web portion, 75 however, at the outer ends being projected downward and flanged at 23, where they rest upon and are riveted to the vestibule ceiling plates 24; this downward extension of the plates being cut out at 25, over the openings 80 in the ceiling plates where the vestibule lamps are located. The outer ends of these end deck-plates, together with the eaves flanges 11 and 12, are curved to conform with the arch of the vestibule roof; the vertical flanges 85 12 being broadened out, where they terminate at 26, to meet and support the lower deck roof sheets at these points, the space between the deck-plate web and the flange 26 being filled in by a flanged plate 27; to the 90 lower edge of which plate the lower deck roof sheets are also riveted. The roof sheet flanges are riveted to the end deck-plates on the line of rivet holes marked 29, and to the flanges 26 on the line of rivet holes marked 95 30. Above the car body corner posts 36, an upper deck carline 14 passes across between these end deck-plates 21, and curved braces 15, extend down to the angle plates 32, which are riveted to the top of the vestibule ceiling 100 plate 24, just back of the end top side-plate 33; the vestibule roof sheets being riveted to these curved end braces. These vestibule roof sheets have their lower edges riveted in with the upper edge of the end top side-plate 105 33, with an eaves molding strip 34 fastened in between, said molding 34 corresponding with the molding 18, which is formed on the longitudinal braces 17. These two moldings 34 and 18 are brought together over the corner posts 36; as shown in Fig. 1.

In this form of the upper car frame, instead of carrying the top end plates 33 around to meet the top side-plates 20, I break said plates away between the corner posts 36 and 115 the vestibule posts 37, and place therebetween lintel plates 35, over the vestibule doors, said lintel plates being riveted in with the eaves molding 34, between the edge of the roof sheets 19, and the upturned flanges of 120 the ceiling plates 24, as shown in Fig. 3. The lintel plates 35 are of pressed steel bent inwardly and riveted to the under side of the ceiling plates, thereby forming stiff connecting braces between the upper ends of the 125 posts 36 and 37. The vestibule end door posts 38 and the car entrance door posts 39, are substantially the same as described in my Letters Patent No. 839,857, granted January 1, 1907, as are also the posts 36 and 37 and 130

the general structural arrangement of the vestibule. Extending between the posts 38 and 39, on each side, I now employ a U-shaped plate 40, to house the vestibule buffer 5 springs, and to act also as a brace between the upper ends of these posts; the flanges of these U-shaped braces 40 being riveted to the under side of the ceiling sheet, as shown in Fig. 3.

10 To brace the extensions 22 on the end side-plates 21, where they are joined to the ceiling plates 24, at their inward ends, I employ gusset plates 42, flanged on their outer and lower edges and riveted to the deck plate 15 webs and to the ceiling plate.

The sashes for the deck lights consist of metal frames 43 flanged around their outer edges and riveted to the deck-plates 5 in each of the openings 10; the window glass being 20 secured in said frames by any suitable means, as by curved plates 44, fastened to the frames by means of screws, as shown in Figs. 6 and 7.

In order to secure the inside sheathing and finish to this framework I provide the stiffening flange 9, and the upper and lower deck carlines, with slotted holes 45, into which bolts may be inserted from inside the car and locked from turning. This feature, however, is reserved for description in a companion 25 application, Serial No. 358,975, filed February 23, 1907, embodying certain improvements in the interior construction for these cars. At 46 and 47 I provide longitudinal 30 inside braces, which, in addition to stiffening the longitudinal connections between the frame posts, also act to support the inside 35 finish.

The foregoing comprises a description of the essential features of my improvements. 40 The details of construction may be varied in form and design without departing from the spirit of my invention.

What I claim as my invention and desire to secure by Letters Patent is—

45 1. In a car frame, the combination, with the frame posts having lower deck carlines formed by inturned extensions from the upper ends thereof, of longitudinal deck-plates having their lower edges flanged outwardly and riveted to the ends of said carline extensions.

50 2. In a car frame, the combination, with the frame posts having lower deck carlines formed by inturned extensions from the upper ends thereof, of longitudinal deck-plates having stiffening flanges formed along their lower edges to which the ends of the carline extensions are riveted, deck side-braces riveted to said carline extensions and to the 55 deck-plates, and upper deck carlines riveted to the deck-plates between opposite side-braces.

55 3. In a car frame, the combination, with the frame posts having lower deck carlines formed by inturned extensions from the

upper ends thereof, of longitudinal deck-plates having stiffening flanges formed along their lower edges above which the ends of the carline extensions are riveted, lower deck roof sheets riveted in place on the outside of 70 said extensions, the upper edges of said roof sheets being flanged and riveted to the deck-plates, and longitudinal brace members riveted to the posts to support the outer edges of said roof sheets.

75 4. In a car frame, the combination with the lower and upper deck carlines of deck-plates extending continuously from end to end of the car, said plates having outturned stiffening flanges formed thereon at top and bottom, substantially as and for the purpose set forth.

80 5. In a car frame, the combination, with the frame posts, of carlines connected to the same and comprising lower deck portions, upper deck portions, and vertical connecting portions, and deck-plates secured to the inner edges of the vertical connecting portions of the carlines and provided with outturned flanges at both top and bottom edges.

85 6. In a car frame, a deck-plate having its upper edge flanged outwardly to receive and support the outer edge of the upper deck roof sheets.

90 7. In a car frame, a deck-plate having its upper edge bent outward on the curve of the upper deck roof and then downward to form an eaves molding, and a roof sheet riveted to said outward bend.

95 8. In a car frame, a deck-plate having 100 stiffening flanges formed along its lower and upper edges and provided at suitable intervals with openings for the deck lights, and sash frames for said lights fastened to the plate at said openings.

105 9. In a car frame, a deck-plate having a stiffening flange formed along its lower edge and an eaves flange formed along its upper edge, the web of the plate being provided at suitable intervals with openings for the deck 110 lights.

110 10. In a car frame having vestibule ceiling plates at each end, a deck-plate having a stiffening flange formed along its lower edge and extending from end to end of the car, in 115 combination with end deck-plates joined thereto at each end and adapted to be fastened directly to the ceiling plates.

115 11. In a car frame having vestibule ceiling plates at each end, a deck-plate having 120 flanges formed along its upper and lower edges and extending from end to end of the car, in combination with end deck-plates having corresponding flanges formed thereon for a portion of their length, said plates being 125 projected downward at their outward ends and riveted to the ceiling plates, having their upper flanged edges curved downward to receive the vestibule roof sheets.

12. The deck side-brace comprising a ver- 130

tical transverse brace member having lateral flanges formed at the top, bottom and inward edge, substantially as herein shown and described.

5 13. The upper deck carlines of U-shaped cross section having outturned flanges at each side, said flanges being faced upwardly, and the flanges and body portion of the carlines being bent down and flattened at each 10 end to form vertical attaching flanges.

14. In a car frame, the combination, with the side frame posts, of longitudinal brace members of U-shaped cross section riveted outside the posts with the flanged edges 15 placed outward and roof sheets riveted to said flanges.

15. In a car frame, the combination with the side frame posts and top side-plates, of longitudinal brace members of U-shaped cross section riveted outside the posts above 20 the top side-plates with the flanged edges placed outward, and roof sheets riveted to said flanges, the lower flange being riveted in between the top side-plates and the roof 25 sheets.

16. The longitudinal brace members of U-shaped cross section having outturned flanges at each side, one of said flanges being off-set to form an eaves molding substantially 30 as shown and described herein.

17. The combination, with the top side-plates and roof sheets of a strip riveted in between the upper edge of the side-plates and the lower edges of the roof sheets and 35 off-set along its lower edge to form an eaves molding.

18. In a car frame, the combination, with the vestibule side door posts and the top side and end plates having their ends riveted thereto, of a ceiling plate passing across between posts and flanged around the sides and ends, and lintel plates having their outward ends riveted in with said flanges between and in alinement with the end and side plates, and their inward sides flanged and 45 riveted to the under side of the ceiling plate, the top end plate being riveted to the flange around the end of the ceiling plate.

19. In a car frame, the combination, with a vestibule ceiling plate having side and end 50 flanges, of a roof sheet having its edges overlapping said flanges, lintel and top end plates having their upper edges inserted between said flanges and the roof sheet, eaves molding strips inserted between said plates 55 and the roof sheet, and a line of rivets fastening all together.

20. In a car frame, the combination, with a vestibule ceiling plate and posts for the car entrance and end vestibule door-ways, of longitudinal brace members of U-shaped cross section, extending between posts at each side of said door-ways and flanged along their upper edges, where they are riveted to the under side of the ceiling plate. 60

In testimony whereof I have affixed my signature, in presence of two witnesses.
